Waluin Crystal Pendant Light Fixture, ASIN: B09V4FM9CP. Date first available at amazon.com—Mar. 9, 2022. (Year: 2022).*

Primary Examiner — Clare E Heflin

(74) Attorney, Agent, or Firm — Heslin Rothenberg Farley & Mesiti P.C.

(57) CLAIM

The ornamental design for a lighting fixture, as shown and described.

DESCRIPTION

FIG. 1 is a front right perspective view from below of a lighting fixture according to the new design;

FIG. 2 is a rear left perspective view from above thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof;

FIG. 8 is a bottom view thereof; and,

FIG. 9 is another perspective view thereof.

The broken lines in the drawings illustrate portions of the lighting fixture and form no part of the claimed design.

1 Claim, 5 Drawing Sheets
